UNITED STATES PATENT OFFICE.

TIMOTHY P. RANDALL, OF ADRIAN, MICHIGAN.

THILL-COUPING.

SPECIFICATION forming part of Letters Patent No. 322,481, dated July 21, 1885.

Application filed May 26, 1885. (No model.)

To all whom it may concern:

Be it known that I, TIMOTHY P. RANDALL, a citizen of the United States, residing at Adrian, in the county of Lenawee and State 5 of Michigan, have invented a new and useful Improvement in Thill-Couplings, of which the following is a specification, reference being had to the accompanying drawings.

My invention relates to thill-couplings, and 10 more particularly to that class in which the draw-iron is provided with a removable plate carrying a journaled thill, the object being to provide improved means for holding said plate in position, and yet allowing it to be 15 readily and easily detached when desired.

With these ends in view the invention consists in the improved construction and combinations of parts hereinafter fully described, and pointed out in the claims.

20 In the drawings, Figure 1 is a perspective view of a thill-coupling constructed in accordance with my invention. Fig. 2 is a transverse vertical section of the same. Fig. 3 is a transverse section showing the device 25 unlocked, and Fig. 4 is a longitudinal vertical section of a modification.

In the accompanying drawings, in which like letters of reference indicate corresponding parts in all the figures, A represents the 30 draw-iron, which is adapted to be attached to the axle by a clip, as usual. The draw-iron A is provided on its upper side with a dovetailed recess, B, to receive a dovetailed plate, C, carrying upwardly-extending ears D, between which the thill-iron is adapted to be 35 journaled, as usual. The draw-iron A is provided with a circular opening, a, on a line with the dovetailed recess upon the upper side of the draw-iron. The said circular opening a terminates at its upper end in an oblong 40 opening, b.

E represents a metallic bushing, which is exteriorly-threaded and engages the opening a in the draw-iron, said bushing being provided 45 at its lower end with an inwardly-extending annular flange or shoulder, c.

F represents a thumb-piece, which is provided at its lower end with a head, d, by which it can be readily turned, and is provided with 50 an annular shoulder at its upper end, from the upper side of which projects an elongated

lug, e, which is adapted to engage the elongated opening b in the draw-iron. A recess, f, is made in the under side of the removable plate carrying the journaled thill, which recess is 55 adapted to be engaged by said lug e, and thus hold the plate against detachment.

For holding the lug e of the thumb-piece in engagement with the recess on the under side of the detachable plate C, a spiral spring, F, 60 is provided, which spiral spring is located on the thumb-piece and bears against the shoulder d' at one end and against the flange c of the bushing at its other end.

The operation is as follows: When it is desired to detach the plate C carrying the thill-iron from the draw-iron, the thumb-piece is pulled downwardly from engagement with the recess on the under side of the plate C, and is then given a quarter-turn. Said thumb-piece 70 is then turned transversely to the position it occupies when locked, thus bringing the elongated lug crosswise of the oblong opening and holding said lug below the upper face of the draw-iron, thus allowing the plate to be readily 75 detached and replaced in position when desired. When the plate is in position, and it is desired to lock the same, the thumb-piece is turned so as to bring the lug of the thumb-piece on a line with the oblong opening, when 80 the spiral spring forces the lug through the opening and into engagement with the detachable plate.

In the modification shown in Fig. 4, in lieu of the spring and bushing, I employ a flat 85 spring, H, and locate the same on the under side of the draw-iron. The said spring H is provided at its forward end with a slot in which the finger-piece is located and in which it is adapted to turn said spring-bearing against 90 a shoulder on the thumb-piece, and thus holding it in engagement with the recess in the plate C.

Having thus described my invention, what I claim, is—

1. The combination, with a draw-iron, of a detachable plate carrying a journaled thill-iron and a spring-actuated thumb-piece to engage openings in the draw-iron and plate, and adapted to be turned substantially as described to hold the parts in an unlocked position, as set forth.

2. The combination, in a thill-coupling, with the draw-iron and a detachable plate located thereon, of a bushing located in an opening in the draw-iron, a thumb-piece working in 5 said bushing, and a spring located on the thumb-piece, as set forth.

3. The combination, with the draw-iron and the detachable plate carrying the journaled thill-iron, of a bushing located in an opening in the draw-iron, a thumb-piece having 10 the head and an elongated lug and adapted

to engage openings substantially as described in the draw-iron and a recess in the detachable plate, and a spring on the thumb-piece, as set forth.

In testimony that I claim the foregoing as my own, I have hereto affixed my signature in presence of two witnesses.

15 TIMOTHY P. RANDALL.
